Jiang(57) **CLAIM**

The ornamental design for a cell phone camera lens, as shown and described.

DESCRIPTION

FIG. 1 is a perspective view showing a cell phone camera lens.

FIG. 2 is a front view of a cell phone camera lens.

FIG. 3 is a rear view of a cell phone camera lens.

FIG. 4 is a top view of a cell phone camera lens.

FIG. 5 is a bottom view of a cell phone camera lens.

FIG. 6 is a side view of a cell phone camera lens; and,

FIG. 7 is an opposite side view of a cell phone camera lens. The broken lines depict portions of the cell phone camera lens in which the design is embodied that form no part of the claimed design.
